UNITED STATES PATENT OFFICE.

JEFFERSON O. ADAMS, OF RAYNE, LOUISIANA.

HARNESS.

Application filed May 25, 1925. Serial No. 32,674.

To all whom it may concern:

Be it known that I, JEFFERSON O. ADAMS, a citizen of the United States, residing at Rayne, in the parish of Acadia and State 5 of Louisiana, have invented new and useful Improvements in Harness, of which the following is a specification.

My present invention pertains to harness; and it contemplates the provision of durable 10 and dependable couplings and arrangements of saddle, breast strap, trace strap and shaft connections.

Other objects and advantageous characteristics will be fully understood from the following description and claim together with the drawings accompanying and forming part of this specification, in which:—

Figure 1 is a side elevation of my novel harness as arranged on a horse.

20 Figure 2 is a view partly in section of harness saddle.

Figure 3 is a top plan view of the saddle.

Figure 4 is a view taken in the plane indicated by line 2—2 of Figure 2 looking in 25 the direction of the arrows.

Figure 5 is a side elevation of a portion of harness showing the connections to the breast strap and trace as well as the connection of the belly strap and saddle.

30 Figure 6 is an edge elevation of Figure 5.

Figure 7 is a sectional view taken in the plane indicated by line 7—7 of Figure 5 looking in the direction of the arrows.

Similar numerals of reference designate 35 corresponding parts in all the views of the drawings.

My novel harness saddle is designated by 1 having a pad 2 of felt or other material and secured by means of stitching 3 to the 40 pad 2 is a covering 4 while studs 5 of rein guides 6 pass through and are riveted to the covering. The studs 5 also bear on a plate 7 that is also riveted indicated by 8 to the covering 4 and said plate 7 is provided 45 with slots 9 that act as guides for the depending strap 10. This strap 10 extends down both sides of the saddle and is provided with a loop ring connection 11 that is provided on the trace 12. This trace 12 is 50 further provided at the forward end with a buckle 13 adapted to engage a breast strap

14 and the trace 12 is also provided with a ring 15 and loops 16. The connection 11 is secured to a short strap 17 that engages a ring 18 that in turn connects with the belly 55 strap 19.

Extending from the saddle is the strap 20 and depending from this strap 20 are straps 21 and 22 that engage the breeching strap 23.

Secured to the strap 21 is a ring 24 that engages the short strap 25 that in turn extends to and is connected with the ring 18 as illustrated.

The invention is extremely simple in construction and the saddle comprised of but a few elements and these of such a nature that weight assured extreme comfort to the draft animal.

At the same time the connection to the 70 saddle of the trace and belly straps is extremely simple and hence inexpensive to produce.

The breast strap moreover is provided with and requires no hold-up strap as it is 75 retained in proper position by the trace.

Manifestly the trace and breast strap are held up by the depending strap 10.

The device illustrated and described constitutes my novel device but I do not care to 80 limit myself to the exact arrangement of elements shown because in the further practice of the invention such changes or modifications may be made as fairly fall within the scope of the appended claim.

Having described my invention what I claim and desire to secure by Letters-Patent, is:—

In a harness, the combination of a saddle, a strap having its ends depending from the 90 saddle, traces having connections secured to the depending ends of said strap, short straps secured to said connections and carrying rings, a belly strap secured to said rings, a breast strap secured to the forward 95 ends of said traces, a breeching strap, and means connecting said breeching strap with the rings to which the belly strap are attached.

In testimony whereof I have hereunto set 100 my hand.

JEFFERSON O. ADAMS.
